UNITED STATES PATENT OFFICE.

ROBERT SHAW CHALMERS, OF COUNCIL BLUFFS, IOWA.

HOT-AIR STOVE.

SPECIFICATION forming part of Letters Patent No. 372,359, dated November 1, 1887.

Application filed March 5, 1886. Serial No. 194,169. (No model.)

To all whom it may concern:

Be it known that I, ROBERT SHAW CHALMERS, a subject of the Queen of Great Britain, residing at Council Bluffs, in the county of 5 Pottawattamie and State of Iowa, have invented certain new and useful Improvements in Hot-Air Stoves; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 of the drawings is a representation of a central vertical section. Fig. 2 is a horizontal section on line x x , Fig. 1.

My invention relates to stoves, heaters, and furnaces; and it consists in the construction 20 and novel combination of parts, as will be hereinafter fully described, and pointed out in the claim.

Referring by letter to the accompanying drawings, A designates the base of the stove; 25 B, the ash-pit; C, the fire-pot, and D the hot-air chamber or inverted-dome section of the stove. A fire-space, E, is left behind the dome D and the body of the stove, and in this fire-space E an inclined deflector, F, which partially encircles the dome D, is placed, and causes the heat to be thoroughly utilized before passing into the chimney. The ash-pit 30 B is provided with a horizontal division-plate, X, which extends forwardly nearly across the ash-pit and forms beneath it the flue which connects with the exit-flue a. By this construction it will be seen that while a sufficient draft is allowed to carry off the smoke through the pipe a the hot air and particles of combustion 35 will be prevented from entering at the lower end of the said flue, but will be carried up through the body of the stove, and thus utilized to heat the cold air in the chamber D. Should it be desirable, an ash-pan might be 40 used, in which case it would be placed upon the division-strip X.

G is a cold-air pipe, which connects with the base-flue H at its lower end and extends up outside of the fire-pot section and enters the 45 hot-air chamber D, near the bottom of the same. Immediately above the cold-air flue G,

the upper end of which is curved inwardly and passes through the wall of the stove-body and connects with the dome D, near the bottom of the latter, is a horizontal deflecting-plate, Y, which extends nearly across said dome, so that the cold air which enters the dome through the flue G will be deflected and caused to travel nearly across the bottom of the drum D before ascending to the pipe K. 55 The pipe a is the smoke flue and conveys the smoke to the chimney. The cold air therefore enters the hot-air chamber near the bottom of the latter and immediately over the fire, so that the cold air becomes quickly highly 60 heated. The dome or hot-air chamber is provided with a hot-air exit, K. The products of combustion partly pass up from the fire-pot around the dome D, and are deflected by the inclined deflector F, interposed between the 65 drum and the wall of the stove, and caused to travel forwardly around the drum D before passing through the flue Z into the pipe a.

The heated air from the hot-air chamber may be admitted to the room in which the 70 stove is located by means of a register; or it may be conveyed to the room above by a suitable flue, if desired.

The operation of my improved heater is as follows: When kindling a fire in the fire-pot 75 C, a damper, n, in a short pipe, Z, is opened, thus giving a direct outlet-draft to the pipe a. When the bed of fuel is in a state of incandescence, the said damper n is closed, thus causing the products of combustion after leaving the fire-pot to ascend into the chamber E and to descend into the ash-pit section B above the plate X. This plate causes all the products to pass to the front of the stove, and then allows them to pass back beneath said 80 plate to the lower end of the pipe a, as indicated by the arrows on Fig. 1. In passing forward over the plate X the products of combustion will receive considerable heat directed downward through the grate, which heat will 85 be radiated into the room from the walls of the ash-pit.

Having described this invention, what I claim, and desire to secure by Letters Patent, is—

80 A hot-air stove comprising the following elements: a fire-pot surrounded by a fire-

chamber communicating at its rear with an ash-pit, a horizontal plate, X, in said ash-pit, adapted to direct the products of combustion forward and then backward, an outlet-pipe, 5 a, leading from the rear part of the ash-pit, an air-heating chamber, D, directly above the fire-pot, provided with a deflecting-plate, Y, a cold-air pipe, G, leading into said chamber D below the said plate Y, with its opposite 10 end opening between the ash-pit and the lower end of the escape flue a, and a direct-draft pipe,

Z, provided with a damper, n, and forming a communication between the chamber E and pipe a when said damper is open, all substantially as described.

In testimony whereof I affix my signature in presence of two witnesses.

ROBERT SHAW CHALMERS.
